AIR PUMP

John R. Oishei, Buffalo, N. Y., assignor to Trico Products Corporation, Buffalo, N. Y.

Application November 30, 1938, Serial No. 243,230

6 Claims. (Cl. 230—141)

This invention relates to fluid pumping devices and more particularly to an improvement in that type of pump which utilizes rotary interengaging impeller members.

It has heretofore been proposed to provide mechanical take-up means in connection with fluid pumps of the type here under consideration. Such take-up devices have usually involved interposing additional mechanical means between the normally contacting wall of the pump casing and the rotary impelling members.

In my present invention the various elements are so arranged that the rotary elements are held in resilient sealing contact directly against the inner wall of the pump casing. This construction simplifies and makes more certain the efficient sealing of the pumping chamber portion of the fluid pump.

In the drawing:

Fig. 1 is an elevational view of my improved pump with the casing cover member removed; and

Fig. 2 is a cross-sectional view taken on the line II—II of Fig. 1.

In the drawing the numeral 10 designates a main casing member which provides a suitable compartment for the operating parts and which is closed with a cover member 11, shown in Fig. 2. Provided within the casing 10 is a projection or abutment 12 having two re-entrant arcuately curved faces, the purposes of which will herein-after be described. The projection 12 is preferably rigidly associated with the casing 10 and in the present instance is illustrated as being integral therewith.

The moving pumping elements are, in the exemplified embodiment, a pair of interengaging gears 13 and 14 which are held in operative engagement by a bracket 15 which has journaled therein the opposite ends of gear supporting stub shafts 16 and 17 respectively. The bracket 15 has spaced parallel bearing portions 18 and 19 and an intermediate connecting portion 20.

In assembling the pump of the present invention the interconnected gears 13 and 14 are disposed in abutment with the projection 12 in such manner that the outer periphery of each gear rides against one of the previously referred to arcuate faces of the element 12 with the element projecting between the gears almost to the point of intersection of their outside diameters.

Portions 21 and 22 which serve to shroud the gears 13 and 14 in the region of their contact with the projection 12 are provided. Such portions could either be a part of the bracket 15 or

integral with the casing 10. In the drawing, however, the portion 21 is formed integrally with the casing 10 and the portion 22 is formed integrally with the cover member 11.

At the point where the element 12 projects farthest between the gears 13 and 14 an aperture 23 is provided which leads to a tube 24 which is connected to the casing 10 by a coupling 25.

One of the impelling members, in the present instance the gear 14, is adapted to be rotated as by means of the flexible drive shaft 26. The drive shaft 26 enters the casing 10 through an opening 27 which is preferably larger than the drive shaft to permit movement of the impelling members in a direction transverse to their axis of rotation. If the gears 13 and 14 be rotated counterclockwise and clockwise respectively as viewed in Fig. 1, the device will function as a vacuum pump, fluid from the tube 24 filling the spaces between the gear teeth as they disengage and being carried thereby to the point where they emerge from contact with the projection 12 where the fluid is delivered into the interior of the casing 10 generally. In the case of a gaseous fluid a vent 28 may be provided to avoid building up of pressure in the interior of the casing.

Means are provided for assuring intimate contact between the peripheries of the impelling members and the cooperating surfaces of the projection 12 at all times. Such means may comprise a coil spring 29, one of whose ends bears against the connecting portion 20 of the gear supporting bracket 15. The other end of the coil spring is received within a cup provided in an adjusting screw 30 which is disposed in a threaded opening in the wall of the casing 10.

The coil spring 29 and the adjusting screw 30 are disposed opposite the projection 12 so that they serve to resiliently hold the gears 13 and 14 evenly against the projection 12. Owing to the particular formation of the arcuate surfaces of the projection 12 and the floating mounting of the bracket 15 which carries the gears 13 and 14 the gears will be self-centering with respect to the projection 12. If desired a boss 31 may be formed upon the back of the connecting portion 20 of the bracket 15 to assist in locating the coil spring 29 thereon.

While a single detailed embodiment of the invention has been illustrated it is to be understood that my invention is not to be considered as limited thereto or in any other way save as defined in the appended claims.

I claim:

1. In a rotary pump, a casing, a pair of inter-

engaging impelling members adapted to be jointly rotated, means rigidly associated with said casing for cooperation with the peripheries of said impelling members to form pump chambers, and movable mounting means for said impelling members whereby said members may be moved transversely to their axes and thereby maintained in intimate peripheral contact with said rigid means, said rigid means having a fluid passage terminating adjacent said impelling members.

2. In a rotary pump, a casing, a pair of inter-engaging impelling members adapted to be jointly rotated, means rigidly associated with said casing for cooperation with the peripheries of said impelling members to form pump chambers, means movably mounting said impelling members within said casing for movement transverse to their axes, and resilient means for urging said impelling members into intimate peripheral contact with said rigid means, said rigid means having a fluid passage terminating adjacent said impelling members.

3. In a rotary pump, a casing, a pair of interengaging impelling members, a bracket for supporting said impelling members for joint rotation, and means associated with said casing for cooperation with the peripheries of said impelling members to form pump chambers, said bracket being movably mounted in said casing for movement of said impelling members in a direction transverse to their axes, said casing associated means having a passage terminating in a port adjacent said impelling members for conducting fluid displaced thereby.

4. In a rotary pump, a casing, a pair of inter-engaging impelling members, a movably mounted bracket for supporting said impelling members for joint rotation, said bracket and said impelling members being bodily movable in a direction transverse to the axes of rotation of said impelling members, means associated with said casing for cooperation with the peripheries of said im-

pelling members to form pump chambers, and resilient means for acting against said bracket to urge said impelling members into intimate peripheral contact with said first mentioned means, said casing associated means having a fluid passage arranged for communication with said pump chambers.

5. In a fluid pump, a casing, a pair of interengaging impelling members, means rigidly associated with said casing and having a pair of re-entrant arcuate faces for bearing against adjacent portions of the peripheries of said impelling members to form pump chambers, a holder for said impelling members for supporting the same in interengaged relationship, said holder being mounted for movement in said casing in a direction transverse to the axes of rotation of said impelling members, and resilient means associated with said casing and acting upon said holder for urging said impelling members against said arcuate faces, said rigid means having a fluid passage arranged for communication with said pump chambers.

6. In a fluid pump, a casing, a pair of interengaging impelling members, means rigidly associated with said casing and having a pair of re-entrant arcuate faces for bearing against adjacent portions of the peripheries of said impelling members, a holder for said impelling members for supporting the same in interengaged relationship, said holder being mounted for movement in said casing in a direction transverse to the axes of rotation of said impelling members, said rigid means including side flanges for cooperation with said impelling members and said arcuate faces to form a pump chamber, and means for supporting said holder with said impelling members in abutment with said arcuate faces, said rigid means having a fluid passage arranged for communication with said pump chambers.

JOHN R. OISHEI.
